[57] CLAIM

The ornamental design for menu printer, substantially as shown and described.

DESCRIPTION

FIG. 1 is a rear elevational view of a menu printer showing our new design;

FIG. 2 is a top plan view thereof;

FIG. 3 is a front elevational view thereof;

FIG. 4 is a bottom plan view thereof;

FIG. 5 is a left side elevational view thereof;

FIG. 6 is a right side elevational view thereof;

FIG. 7 is a top right perspective view thereof; and

FIG. 8 is a top left perspective view thereof, the broken line showing of card and paper being illustrative of environment only.
